CENTRIFUGAL SEPARATING MACHINE

Joseph S. Pecker, Philadelphia, Pa., assignor to
 American Centrifugal Corporation, New York,
 N. Y., a corporation of Delaware

Application April 28, 1934, Serial No. 722,952

29 Claims. (Cl. 210—63)

The invention relates to an automatic centrifugal separating machine.

One object of the present invention is to provide an automatic centrifugal separating machine having a horizontal rotary centrifugal sludge dewatering basket and provided with a lower clarification tank for the effluent and equipped with a superimposed mixing tank in which the material prior to being fed to the rotary centrifugal basket may be treated with air, steam, chemicals, or otherwise, to facilitate dewatering the sludge and effecting separation of the liquids and solids, means being also provided for giving the effluent collecting in the tank the desired treatment so that the effluent may be clarified to the desired or necessary degree prior to draining it from the tank.

A further object of the invention is to provide an automatic centrifugal separating machine of this character wherein purging and cleaning are performed at high speed and the effluent discharged substantially tangentially through seepage means upon an annular series of vanes adapted through the reaction of the discharge effluent to conserve energy and at the same time dissipate the force of the impact of the effluent and facilitate collecting the same and delivering the effluent to the collecting and sedimentation tank.

Another object of the invention is to provide a centrifugal separating machine having a horizontal rotary centrifugal basket provided with valve controlled sludge discharge ports and equipped with exteriorly arranged means for sweeping extruded solids to a sludge outlet opening and for expelling such extruded sludge tangentially through the outlet opening.

A further object of the invention is to provide a centrifugal separating machine having a horizontal rotary centrifugal basket and provided at the ends thereof with means for feeding the material from the superimposed tank into the basket to distributing means adapted through centrifugal action to spread the material and throw the same to the peripheral portions of the basket.

A further object of the invention is to provide a centrifugal separating machine having a rotary horizontal centrifugal basket divided into two symmetrical chambers into which the material to be dewatered may be fed either simultaneously or independently and distributed centrifugally to the peripheral portions of the chambers and the effluent discharged at the outer portions of the chambers and the dry solids ex-

truded at the inner portions of the said chambers so that the purging and cleaning periods of the two chambers may coincide or one chamber may be purging while the other is extruding the dry solids and vice versa.

A further object of the invention is to provide a centrifugal separating machine having a mixing chamber provided with means for thoroughly beating, cutting, stirring and agitating the material to be dewatered prior to its introduction into the rotary centrifugal basket and also having means for feeding to the mixing chamber chemicals, steam, air, inert material such as pulp, sawdust or sand or any other reagent to facilitate effective separation of solid and liquid matter in the rotary centrifugal basket.

With these and other objects in view, the invention consists in the construction and novel combination and arrangement of parts herein-after fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

Fig. 1 is a central vertical sectional view of a centrifugal separating machine constructed in accordance with this invention.

Fig. 2 is a vertical sectional view on the line 2—2 of Fig. 1.

Fig. 3 is a horizontal sectional view on the line 3—3 of Fig. 2, parts being omitted.

Fig. 4 is a vertical sectional view on the line 4—4 of Fig. 1.

Fig. 5 is a vertical sectional view on the line 5—5 of Fig. 1.

Fig. 6 is a vertical sectional view on the line 6—6 of Fig. 1.

Fig. 7 is a detail sectional view of a portion of the rotary centrifugal basket showing the valve arranged for purging in the left hand chamber of the basket and for extruding dry sludge from the right hand chamber of the basket.

Fig. 8 is a similar view showing the valve arranged for purging in the right hand chamber of the basket and for extruding dry sludge from the left hand chamber of the basket.

In the accompanying drawings in which is illustrated the preferred embodiment of the invention the centrifugal separating machine comprises in its construction a frame or casing preferably provided with a substantially cylindrical

housing 1 divided approximately centrally into upper and lower sections 2 and 3 and having a hollow supporting base 4 and a superimposed tank 5 preferably formed integral respectively with the lower section 3 and the upper section 2, but the frame or casing may be constructed in any other suitable manner as will be readily understood. The meeting edges of the upper and lower approximately semi-cylindrical sections 2 and 3 of the housing are provided with outwardly extending horizontal marginal flanges 6 and 7 which are designed to be detachably bolted together for enabling the sections to be readily separated and assembled.

15 The cylindrical housing is provided with removable side plates 8 of substantially circular form bolted at their marginal portions 9 to the sections 2 and 3 at the side edges thereof and adapted to be readily assembled and removed to permit the assembling and removing of a horizontal rotary centrifugal basket 10. The side plates 8 are provided at their inner faces with inwardly extending annular flanges 11 substantially L-shaped in cross section and forming annular effluent troughs 12 arranged to receive seepage from the rotary centrifugal basket.

The side plates are provided at their upper portions with approximately semi-circular flanges 13 arranged in parallelism with the adjacent portions of the flanges 11 and curved in cross section to form grooves 14 arranged concentric with the troughs and adapted to receive effluent and facilitating the collecting of the same and the delivery of the effluent to the tank 15 formed by the hollow base 4. The curved flanges 13 extend around the upper portions of the side plates 8 and the flanges 11 are provided at the lower portions of the side plates with approximately semi-circular grooves 16 located in the bottom of the annular troughs 12 and receiving therefrom the seepage which is conducted to the tank 15 by side drain pipes 17 arranged exteriorly of the housing at opposite sides thereof and communicating with the interior of the same and with the tank, as clearly illustrated in Fig. 1 of the drawings. The flanges 11 are provided within the troughs 12 with an annular series of vanes 18 spaced apart, as clearly illustrated in Fig. 4 of the drawings, and curved inwardly of the housing and adapted to present concave faces to the seepage discharge by the rotary centrifugal basket, as illustrated in Fig. 4 of the drawings, in which the arrow indicates the direction of rotation of the centrifugal basket with relation to the vanes. The vanes are adapted to receive the impact of the effluent which is discharged tangentially against the concave surfaces of the vanes to conserve energy and to facilitate collecting the seepage and draining the same into the tank 15.

60 At the same time the seepage is agitated and aerated to facilitate settling and clarification of the same in the tank 15. The side drain pipes 17 are preferably L-shaped, as shown, with their terminals suitably secured in openings in the side plates 8 and the top of the tank 15 suitable unions 19 being provided for facilitating the assembling of the drain pipes and their removal should the same become necessary.

The horizontal rotary centrifugal basket consists of a substantially cylindrical body portion tapered from the center to the sides of the machine and provided at the center with a vertical web 20 dividing the centrifugal basket into two side chambers 21. The centrifugal basket is provided at the outer smaller ends of the chambers 21

with annular seepage plates 22 constructed substantially the same as the seepage plate shown and described in my co-pending application Serial No. 712,390, filed February 21, 1934, and bolted or otherwise secured to the ends of the oppositely tapered body portion of the rotary basket. The seepage plates are provided with channels or passages 23 arranged to discharge the seepage tangentially from the rotary centrifugal basket, as indicated in Fig. 4 of the drawings.

10 The seepage plates 22 are provided with screens 24 constructed substantially the same as those shown and described in the aforesaid application and adapted to prevent the seepage openings or passages from becoming clogged by fibers contained in the material operated on by the centrifugal basket. As the particular construction of the seepage means is not claimed in the present application but is claimed in the said application and as seepage means of any desired construction may be employed further description and detail illustration thereof are deemed unnecessary in the present application. The seepage passages extend outwardly and discharge the seepage at an angle to the radius intersecting the outer end of the seepage passage so that in the rotation of the centrifugal basket the seepage is discharged approximately tangentially from the basket against the said vanes 18.

20 The annular seepage plates which form the end walls of the horizontal rotary centrifugal basket provide central openings 25 through which extend the ends of a horizontal shaft 26 upon which the rotary centrifugal basket is mounted. The central vertical web 20 of the basket is provided with an integral hub 27 which is mounted on a central cylindrical portion 28 of the horizontal shaft 26.

30 The shaft 26 which is mounted in suitable bearings 29 and 30 is provided at the ends of the cylindrical portions 28 with reductions 31 on which are mounted vertically disposed distributing disks 32 provided with central hubs 33 and secured against the ends of the hub 27 by nuts 34 arranged on threaded portions 35 of the shaft 26, washers 36 being preferably interposed between the nuts and the distributing disks 32, as clearly illustrated in Fig. 1 of the drawings. The threaded portions 35 of the shaft 26 are of a slightly less diameter than the cylindrical portions 31 and are of slightly greater diameter than the end portions of the said shaft 26.

40 The centrifugal basket is preferably keyed to the shaft as shown in Fig. 2 of the drawings, and any other suitable means may, of course, be employed for securing the distributing disks to the horizontal shaft 26. The bearings 29 and 30 which are mounted on the side plates 8 may be of any desired construction and the material to be dewatered is fed to the chambers 21 of the rotary centrifugal basket by means of side feed pipes 37 having upper and lower arms 38 and 39 and provided between the same with a standard valve 40 for controlling the flow of material through the side feed pipes 37. The upper arms 38 of the side feed pipes are secured to the tank 5 at the ends thereof and the end walls of the tank are provided at the bottom with openings 41 for permitting material after the same has been operated on within the tank to be fed from the lower portion of the tank to the centrifugal basket.

50 The upper arms 38 are preferably flanged and bolted to the end walls of the tank, but any other means may, of course, be employed for this purpose, and the lower arms 39 which are slightly 55

inclined extend through the central openings 25 in the end walls of the basket into the chambers 21 and are provided with laterally deflected vertically elongated nozzles 42 set at an angle and arranged to discharge the material against the outer faces of the vertical distributing disks 32 whereby the disks through their rotation with the centrifugal basket are adapted to throw the material radially to the peripheral portions of the centrifugal basket. A uniform distribution within the centrifugal basket of the material to be dewatered by the same is effected through the feeding of the material to the vertical distributing disks and the material is simultaneously fed into the basket at opposite sides of the machine. The valves 40 are of the standard type and are designed to be operated automatically at definite periods, as explained in the aforesaid application. The side plates 8 are provided at their upper portions with openings 43 for the passage of the lower arms 39 of the side feed pipes which are preferably located above the bearings 29 and 30 for delivering the material to the distributing disks at the upper portions thereof.

The rotary centrifugal basket is provided in its cylindrical body portion with annular series of tapered outwardly flared sludge discharge ports 44 located at the inner larger ends of the chambers 21 so that the peripheral walls of the chambers increase in diameter towards the annular series of ports 44 and slope towards the same to assist in the discharge of the sludge through the said ports by the centrifugal action of the machine when a sufficient quantity of the substantially dewatered sludge has accumulated in a cake on the sloping walls of the basket. The discharge of the dewatered sludge through the annular series of ports 44 is controlled by a valve consisting of a cylindrical sleeve 45 provided with openings 46 and 47 adapted through the sliding of the valve on the basket longitudinally of the body portion thereof to carry the openings 46 and 47 into and out of register with the openings 44 of the centrifugal basket. The valve sleeve 45 is guided by keys 46^a mounted on the body portion of the basket at the exterior thereof and arranged in slots 47^a in the valve sleeve 45, but any other suitable means may, of course, be employed for guiding the valve sleeve in its sliding movement longitudinally of the body portion of the basket. The valve sleeve 45 is provided at one side portion of the basket with an extension 48 having spaced annular flanges 49 forming a groove 50 for the reception of shoes 51 which are provided with pivots 52 for connecting the shoes to the lower ends 53 of arms 54 of a horizontal rock shaft 55.

The rock shaft 55 which is located above the basket and which is disposed transversely with relation to the body portion of the basket is journaled in suitable bearings 56 in the upper section 2 of the housing 1 at opposite sides thereof, as clearly illustrated in Fig. 2 of the drawings, and the arms 54 which extend downwardly from the rock shaft 55 are curved concentric with the rotary centrifugal basket and are provided at their lower ends 53 with suitable bearing openings for the reception of the pivots 52 of the shoes which loosely engage the groove 50 and permit rotary movement of the valve without interfering with the pivotal connection between the shoes 51 and the arms 54 of the rock shaft 55. The rock shaft 55 is provided at one end with a crank disk 57 having a wrist pin 58 for connecting the rock shaft with suitable oper-

ating mechanism which may be an electrical, pneumatic or hydraulic control for operating the valve at predetermined intervals and as any suitable control mechanism may be provided for operating the rock shaft 55 illustration thereof is 5 deemed unnecessary.

The dry or dewatered sludge exuded through the ports 44 is discharged into an annular sludge trough formed by spaced annular flanges 58 and 59 located within the cylindrical housing 1 and formed integral with the upper and lower sections thereof and providing an annular passage-way for the said dry or dewatered sludge.

The dry or dewatered sludge exuded through the ports 44 is swept around the annular channel 15 60 by revolving blades 61 carried by the centrifugal basket in the rotary movement thereof and preferably formed integral with and extending radially from the valve sleeve 45, as clearly illustrated in Fig. 5 of the drawings. The centrifugal basket and the valve sleeve rotate in the direction of the arrow in Fig. 2 of the drawings and the blades 61 present flat faces to the exuded sludge and extend from the valve sleeve to within close proximity to the wall of the annular sludge channel 60. These blades are preferably braced by webs 62 formed integral with the blades and with the valve sleeve, but any other suitable construction of blade may, of course, be provided for sweeping the sludge around the annular channel 60 between the rotary centrifugal basket and the housing which is provided at the bottom of the said annular space at one side of the machine with a sludge outlet 63 through which the sludge is discharged tangentially through centrifugal action and also the mechanical action of the blades 61. Any suitable means may be provided for conveying the sludge from the machine.

The clearer effluent is removed from the tank 15 by means of clear effluent drain pipes 64 having a branch or section 65 extending into the tank and provided with a stand pipe inlet 66 extending upwardly to the upper portion of the tank 15 to receive the overflow when the liquid within the tank rises above the upper end of the stand pipe inlet of the drain pipe 64.

The tank is also provided at its lower portion with a sedimentation sludge drain pipe 67 communicating with the interior of the tank at the lower portion thereof, as clearly illustrated in Fig. 2 of the drawings. The sedimentation sludge may be permitted to drain from the tank 15 or it may be removed by vacuum means and the latter may also be employed for removing the clearer effluent if desired as explained and claimed in my copending application filed April 12, 1934, Serial No. 720,333. The tank is also provided at the top with an inlet 68 adapted to permit the effluent within the tank 15 to be treated chemically, with currents of air or any other means, for purifying and clarifying the effluent so that the effluent when drawn off through the clear effluent drain pipes 64 will be in as unobjectionable condition as desired.

The superimposed tank which is preferably provided with a curved bottom 69 has vertical side and end walls and is provided in its end walls with suitable bearings 70 and 71 for the reception of a horizontal shaft 72 provided with revolving cutters 73 fixed to the shaft at spaced points and arranged to cooperate with stationary vertical cutters 74 mounted upon and extending upwardly from the bottom of the tank 5.

The bottom of the tank 5 preferably constitutes a portion of the top of the housing and the 75

vertical cutter blades 74 are arranged at intervals to provide spaces for the revolving cutter blades which pass through the spaces between the stationary cutter blades. The stationary cutter blades are preferably arranged in a straight row, as shown, and the end cutters of the stationary row are spaced from the end walls of the tank to provide the necessary space for the end cutters of the horizontal shaft. The revolving cutter blades of the horizontal shaft are preferably staggered and arranged alternately at diametrically opposite points on the same. The revolving cutter blades 73 of the shaft 12 tend to cut and mix the material as they revolve and they coact with the stationary blades in this mixing and cutting of the material, thoroughly beating, cutting, stirring and agitating the sludge prior to emission from the tank to the centrifugal basket for dewatering. The cutter blades which are straight are beveled at their side edges and tapered at their outer ends to provide cutting edges which are curved at their outer terminals.

The horizontal shaft 26 upon which the rotary basket is mounted is connected by a standard type flexible coupling 75 with shaft 76 of an electric motor 77 which rotates the centrifugal basket at high speed for both purging and cleaning. Any other suitable means may, of course, be employed for connecting the shaft 76 of the motor with the horizontal shaft 26 of the rotary basket.

The motor 77 is mounted on a suitable pedestal 78 which is supported by the base 4 and the clutch 75 which couples the motor to the shaft 26 and uncouples the basket from the motor may be of any desired construction and as an ordinary clutch mechanism is employed detailed description and illustration thereof is deemed unnecessary.

40 The motor is located at one side of the machine and the shaft 26 is provided at the opposite side thereof with a sprocket pinion 79 which meshes with a sprocket chain 80 and the latter is arranged on a sprocket wheel 81 suitably connected with one end of the shaft 12. While sprocket gearing is illustrated for transmitting motion from the basket carrying shaft to the shaft 12 any other suitable gearing may, of course, be provided and in practice a suitable clutch will be provided for connecting the sprocket pinion 79 to the shaft and it will be apparent that manually operable clutch mechanism or automatically controlled clutch mechanism may be provided for enabling the cutter to be operated continuously while the machine is in operation or at intervals.

60 The material to be dewatered is fed into the tank at the top thereof centrally of the same through a main feed pipe 82 which is connected with the opening 83 in the top 84 of the tank by a fitting 85 having branches 86 and 87 for the reception of auxiliary pipes 88 and 89 for enabling air, steam, chemicals, pulp or other inert material reagent for preparing the sludge for effective separation.

65 The top 84 of the tank 5 is slightly dome-shaped as shown in Figs. 1 and 2 of the drawings, and is provided at the opening 83 with an annular boss into which a nipple 90 of the fitting is suitably secured and the said fitting is provided at the annular boss with a flange 91 which fits against the boss and supports the fitting. Any other suitable means, may however, be employed for connecting the main feed pipe 82 and the auxiliary pipes 88 and 89 with the tank.

In the operation of the machine the sewage or other material to be dewatered is fed into the tank through the main feed pipe 82 and is operated on by the cutting blades and during such operation the material may be chemically or otherwise treated for preparing it for effective separation of the liquid and solid matter. After thoroughly beating, cutting, stirring and agitating the material the mixed sludge is drawn off through the valves 40 and conveyed by the side 10 feed pipes to the chambers of the horizontal rotary centrifugal basket and is discharged against the vertically disposed revolving distributing disks which throw the material through centrifugal action to the peripheral portions of the basket. 15 During the feeding of the material into the chambers of the centrifugal basket the sludge discharge ports thereof are closed and the material is fed continuously while the basket is rotating at high speed until a cake of sufficient thickness has 20 been built up on the walls of the body portion of the basket.

At this point the automatic valves will shut off the flow of material to the centrifugal basket and the sliding cylindrical valve will be operated to 25 carry the openings 46 and 47 into registration with the annular series of sludge discharge ports 44. The sludge will be extruded through the sludge discharge ports by the action of centrifugal force aided by the inclined surfaces formed by 30 the oppositely tapered portions of the body of the basket. As the sludge is thrown out radially through the ports of the centrifugal basket it will be confined in the channel 60 formed by the spaced annular ribs or flanges 58 and 59 and 35 will be swept around the cylindrical housing by the blades 61 and discharged tangentially through the opening 63 through centrifugal action and also through the mechanical action of the sludge sweeping blades 61.

40 The seepage means operates at right angles to the direction of the centrifugal force for permitting the escape from the basket of seepage of liquids from the solid material impacted on the imperforate tapering walls of the basket and the effluent is discharged substantially tangentially from the peripheries of the annular end plates of the basket against the annular series of vanes for the purposes heretofore explained.

45 The effluent is drained off into the tank 15 50 and is permitted to settle therein so that the clearer effluent can be drawn off through the stand pipe inlet 66 of the clear effluent drain 64. The effluent in the tank may be treated with chemicals through the inlet pipe 68 or flocculated 55 by the injection of air through the said pipe 68 or some other suitable inlet. The sedimentation sludge may be drawn off through the drain pipe 67 which is connected with the tank adjacent the bottom thereof.

60 The machine is designed to be continuous in its operation and the purging and cleaning operations are performed at high speed and in practice suitable control mechanism will be employed for automatically operating the valves for controlling 65 the feed of material to the chambers of the basket and for also opening and closing the slidable sleeve valve which controls the sludge discharge ports.

70 In order to adapt the valve sleeve 45 for controlling the sludge discharge ports of the rotary centrifugal basket so that the purging operation may be performed in either chamber of the basket while the dry sludge is being extruded from the other chamber of the basket, the said valve sleeve 75

is provided with an annular series of openings 47^b located adjacent the extension 48 of the valve sleeve. The annular series of openings 46 are located at one side of the series of openings 47^b and the series of openings 47^b are located at the opposite side of the openings 47. This will enable the valve to be shifted as illustrated in Fig. 7 of the drawings to bring the openings 47^b into register with the sludge discharge ports of the 10 right hand chamber of the basket, as shown in Fig. 7, for enabling the sludge to be extruded from the right hand chamber of the basket while the operation of purging is taking place in the left hand chamber of the basket, the sludge discharge 15 ports thereof being covered or closed by a portion of the slidable sleeve. The openings 47 are adapted, as illustrated in Fig. 8 of the drawings, to be carried into register with the sludge discharge ports of the left hand chamber of the basket, as 20 shown in Fig. 8, while the sludge discharge ports 44 of the right hand chamber are covered or closed by the sleeve. This arrangement of the valve will enable the sludge to be extruded from the left hand chamber of the basket while the 25 operation of purging is taking place within the right hand chamber of the basket.

What is claimed is:—

1. A centrifugal separating machine including a housing provided with a sludge channel and 30 having an outlet communicating with the channel, a rotary centrifugal basket having sludge discharge ports arranged to discharge sludge by centrifugal force into the said channel, a valve sleeve slidable on and rotating with the said basket and provided with portions arranged to cover and uncover the sludge ports, means for rotating the basket, means for operating the valve sleeve while the basket is rotating, and blades mounted on the valve sleeve and operating in the channel 40 for sweeping the sludge through the channel to the said outlet.

2. A centrifugal separating machine including a housing provided with a substantially annular sludge channel and having an outlet communicating with the channel, a horizontally disposed 45 rotary centrifugal basket having peripheral sludge discharge ports arranged to discharge sludge by centrifugal force into the said channel, a valve sleeve slidable on and rotating with the said basket and provided with portions arranged to cover and uncover the sludge ports, means for rotating the basket, means for operating the valve sleeve while the basket is rotating, and means mounted on the valve sleeve and operating in the 50 channel for sweeping the sludge through the channel to the said outlet.

3. A centrifugal separating machine including a housing provided with oppositely disposed spaced annular troughs, a rotary centrifugal basket disposed in the housing and having its ends operating over said troughs, said troughs having outlets, the basket having an internal web dividing the basket into separate sludge receiving chambers, means for supplying the sludge to said chambers, 60 seepage means in the outer ends of said chambers for discharge of effluent from the chambers into the respective troughs, the chambers having sludge discharge ports in the side walls thereof leading from the interior thereof, the housing 65 having spaced flanges projecting inwardly toward the side walls of the basket and therewith cooperating to provide a sludge receiving channel, means for rotating the basket, means to cover and uncover said sludge discharge ports and to maintain the said ports closed during separation of the 70

liquids from the sludge material and for uncovering the sludge ports subsequent to separation of the liquids from the sludge for discharge of the separated sludge from the basket through said sludge ports into said channel, and means for 5 conveying the material through said channel, the channel having an outlet.

4. A centrifugal separating machine including a casing provided with an effluent receiving tank at its lower portion, a sludge receiving tank at its upper portion and an intermediate basket receiving chamber between said tanks provided with annular effluent receiving troughs at the sides thereof, means for feeding material to said sludge receiving tank, a basket journaled in the intermediate chamber of the casing and having its ends operating over said troughs, said troughs having communication with said effluent receiving tank, said intermediate chamber having inwardly directed spaced annular flanges cooperating with 20 the basket intermediate the ends thereof to provide a sludge discharge channel having an outlet, said basket having an internal web dividing the basket into separate sludge receiving chambers, seepage means in the outer ends of said 25 chambers for discharge of effluent from the basket chambers into said troughs, said basket chambers having sludge discharge ports in the side walls thereof leading from the interior thereof and disposed in alignment with said sludge discharge 30 channel, means to cover and uncover said sludge discharge ports, means for rotating the basket, means for agitating the material in said sludge receiving tank, means for conveying the agitated material to either or both of said basket chambers, 35 means for spreading the material delivered to the basket chambers toward the outer ends of the chambers, means operable to uncover the ports of either chamber or both of them simultaneously for the discharge by centrifugal action 40 of the sludge separated from the liquids in the chambers of the basket to said sludge discharge channel, and means for feeding the material discharged into said sludge receiving channel 45 through the latter.

5. A centrifugal separating machine including a horizontally disposed rotary centrifugal basket provided with an imperforate transverse web dividing the basket into oppositely disposed chambers and blocking the chambers from communication with each other at their inner ends, each chamber having the inner end of its side wall provided with sludge discharge ports adjacent to and on opposite sides of said web and spaced from said web, a valve sleeve mounted intermediate the ends 50 of the basket in embracing relation therewith for sliding movement on the side wall of the basket in opposite directions to selectively cover and uncover the sludge ports of both chambers or to uncover the sludge ports of one chamber only, means 60 for rotating the basket, and means for operating the valve sleeve during rotation of the basket.

6. A centrifugal separating machine including a horizontally disposed rotary centrifugal basket provided with an imperforate transverse web dividing the basket into oppositely disposed chambers and blocking the chambers from communication with each other at the inner ends thereof, the side walls of the basket having sludge discharge ports formed therein leading from the 70 chambers on opposite sides of said web, a shaft on which said basket is secured, disks secured on said shaft and located on opposite sides of said web, means for supplying material to the chambers including pipes extending through the outer 75

end walls of the respective chambers into close proximity to said disks for discharge of the material therefrom against said disks as the basket and disks rotate, and a valve sleeve mounted intermediate the ends of the basket in embracing relation with the basket for sliding movement on the side walls of the basket laterally thereof in opposite directions to selectively cover and uncover the sludge ports of both chambers simultaneously or to uncover the sludge ports of one chamber only, and means for operating the valve sleeve during rotation of the basket.

7. A centrifugal separating machine including a horizontally disposed rotary centrifugal basket provided with an internal web dividing the basket into two separate side-by-side chambers, each chamber being provided with seepage means at the outer end wall thereof, means for supplying material to the chambers for separation, means for rotating the basket to separate the liquids from the solids to build up a wall of solids against the interior surfaces of the side walls of the chambers from the outer ends of the latter to said web without seepage of the solids through said seepage means and to discharge the liquids through said seepage means as the basket rotates, the basket being provided intermediate its ends with separate series of sludge ports leading from said chambers adjacent said web on opposite sides of the latter, means for closing said ports during separation of the liquids from the solids and the discharge of the liquids through the seepage means and subsequently operable to uncover said ports to effect discharge of the wall of solids from the chambers through said ports by centrifugal action.

8. A centrifugal separating machine including a horizontally disposed rotary centrifugal basket having two side-by-side chambers, means for rotating the basket to separate liquids from solids and build up a wall of solids against the inner surface of the side walls of said chambers, each chamber being provided with seepage means at the outer end wall thereof for the passage of the separated liquids from the chambers as the solids are built up against the inner surface of the side walls of the chambers, each chamber having a plurality of sludge discharge ports arranged in the side walls of the chambers and leading from the interior of the chambers for discharge of the built-up wall of solids from the chambers, and means normally closing said sludge discharge ports during the separating operation and operable for movement away from said ports after the separating operation to effect discharge of the wall of solids through said ports by centrifugal force while the basket is rotating.

9. A centrifugal separating machine including a horizontally disposed rotary centrifugal basket provided with an internal web dividing the basket into two separate side-by-side chambers, each chamber being provided with seepage means in the outer end wall thereof and each having an annular series of sludge discharge ports in its side walls leading from the interior of the chambers adjacent to and on opposite sides of said web, the chambers being usable for separation of material together or independently of each other and said web blocking material in one chamber from passage into the other chamber, and means for feeding material to the separate chambers for separation.

10. A centrifugal separating machine for dewatering sewage sludges including a horizontal rotary centrifugal basket provided with an im-

perforate transverse web dividing the basket into two side-by-side chambers and preventing the passage of liquids and solids from one chamber to the other, whereby the two chambers are independently and simultaneously operable, said basket being provided at the outer ends of the side chambers with seepage means and having openings in its side walls adjacent the transverse web and at opposite sides of the same for the discharge of dewatered sludge, and means slideable on the periphery of the basket for covering and uncovering the said openings to permit the side chambers to discharge dewatered sludge simultaneously or independently from the basket.

11. A centrifugal separating machine for dewatering sewage sludges including a horizontal rotary centrifugal basket provided with an imperforate transverse web dividing the basket into two side-by-side chambers and preventing the passage of liquids and solids from one chamber to the other, whereby the two chambers are independently and simultaneously operable, said basket being provided at the outer ends of the side chambers with seepage means and having openings in its side walls adjacent the transverse web and at opposite sides of the same for the discharge of dewatered sludge, and a valve sleeve slideable laterally on the periphery of the basket and having openings movable into and out of register with the sludge discharge openings of the basket to permit the chambers to discharge dewatered sludge either simultaneously or independently.

12. A centrifugal separating machine for dewatering sewage sludges including a horizontal rotary centrifugal basket having an imperforate web dividing the basket into separate side-by-side chambers and preventing the passage of liquids and solids from one chamber to the other, whereby the chambers may be used simultaneously or independently, the chambers having outlets, vertically disposed disks arranged within the chambers and spaced from the imperforate web and rotating with the basket, and sludge delivering means extending into the chambers from the ends of the basket and including feed pipes having their ends adjacent the disks and thereat laterally deflected and vertically elongated to discharge sludge against the vertical distributing disks.

13. A centrifugal separating machine for dewatering sewage sludges including a horizontal rotary centrifugal basket having an imperforate web dividing the basket into separate side-by-side chambers and preventing the passage of liquids and solids from one chamber to the other, whereby the chambers may be used simultaneously or independently, said chambers having outlets and the basket being open at its ends, vertical distributing elements mounted within the chambers and rotating with the basket, and side feed pipes extending into the open ends of the basket and having nozzles directed laterally of the pipes and located adjacent said distributing elements in position to discharge the sludge against the same.

14. A centrifugal separating machine including a rotary centrifugal basket having tapering ends and an intermediate annular portion presenting an exterior substantially cylindrical surface provided with sludge discharge ports leading from the interior of the basket, seepage means in the ends of the basket leading from the interior thereof for the passage of liquids from the basket, and an annular perforated valve member slideable laterally of the basket on said substantially cylind-

drical exterior intermediate surface of the basket to cover and uncover said sludge discharge ports.

15. A centrifugal separating machine including a basket having tapering ends and an intermediate annular portion presenting an exterior substantially cylindrical surface and provided with an interior transverse imperforate web intermediate its ends dividing the basket into separate chambers, said substantially cylindrical exterior surface having sludge discharge ports arranged on opposite sides of said transverse web and leading from the interior of the chambers for discharge of sludge therefrom, seepage means in one of the walls of each chamber of the basket leading from the interior of the chambers for the passage of liquids from the chambers, an annular perforated valve member slidable laterally of the basket on said substantially cylindrical intermediate exterior surface to cover and uncover said sludge outlet ports, means for supplying material to the chambers simultaneously or separately, and means for operating said valve member for coaction of the perforations thereof with the sludge discharge ports to discharge sludge from the chambers simultaneously or separately while the basket is rotating.

16. A centrifugal separating machine including a housing, a rotary centrifugal basket mounted in the housing provided with non-communicating chambers and provided with seepage means at their outer ends to permit seepage of liquids from the basket chambers and provided adjacent their inner ends with separate sets of annular series of sludge discharge ports for the discharge of sludge from the chambers by centrifugal action of the basket, a valve means slidable on the basket and having portions arranged to cover and uncover said ports and provided with a groove, a shoe engaging the said groove, a rock shaft journaled in the housing above the basket and having an arm pivotally connected with the said shoe for sliding said valve means to cover and uncover said sludge discharge ports, and means for rotating the basket.

17. A centrifugal separating machine including a housing, a horizontal rotary centrifugal basket provided with non-communicating side chambers and having seepage means to permit seepage of liquids from the basket and provided at their inner ends with annular series of sludge discharge ports for discharging sludge from the chambers by centrifugal force as the basket rotates, means for rotating the basket, a valve consisting of a cylindrical sleeve slidable laterally on the basket and having portions arranged to cover and uncover the sludge discharge ports and provided with an annular groove, a rock shaft journaled in the housing above the basket and provided with arms located at opposite sides of the basket, shoes pivotally connected with the arms of the rock shaft and engaging the annular groove of the valve, and means for operating the rock shaft to operate the valve sleeve.

18. A centrifugal separating machine including a housing provided with a substantially annular sludge receiving channel having an outlet, a horizontally disposed rotary centrifugal basket having an intermediate portion coacting with said channel and in such portion provided with a sludge discharge port leading from the interior of the basket, means to rotate the basket to separate liquids from solids and retain the solids in the basket, a valve slidable on the basket between the ported portion thereof and said channel for covering and uncovering said sludge discharge port to prevent

discharge of sludge through said port during the separation of liquids from solids while the basket rotates and subsequently operable to permit discharge of sludge through said port into said channels while the basket rotates incident to centrifugal force.

19. A centrifugal separating machine including a housing provided with a substantially annular sludge receiving channel having an outlet, a horizontally disposed rotary centrifugal basket having an intermediate portion coacting with said channel and in such portion provided with a sludge discharge port leading from the interior of the basket, means to rotate the basket to separate liquids from solids and retain the solids in the basket, a valve slidable on the basket between the ported portion thereof and said channel for covering and uncovering said sludge discharge port to prevent discharge of sludge through said port during the separation of liquids from solids while the basket rotates and subsequently operable to permit discharge of sludge through said port into said channels while the basket rotates incident to centrifugal force, and means for positively carrying the sludge through said channel to and through the outlet of the channel.

20. A centrifugal separating machine including a housing, a rotary centrifugal basket provided with tapering ends and an annular intermediate portion presenting an exterior substantially cylindrical surface, a transversely disposed web in the basket dividing the basket into separate non-communicating chambers, seepage means in the chambers leading from the interior thereof for the discharge of liquids from the chambers, said exterior substantially cylindrical surface of the basket being provided with sludge discharge ports on opposite sides of said web leading from the separate chambers, the housing having inwardly-directed substantially-annular flanges cooperating with the housing and with the basket to provide a sludge discharge channel arranged in alignment with said sludge discharge ports, an annular perforated valve member slidable laterally of the basket on said substantially cylindrical intermediate surface of the basket to cover and uncover said sludge discharge ports separately with relation to one chamber or the other or simultaneously with respect to both chambers while the basket rotates, said valve being interposed and operating between the periphery of the basket and said discharge channel, means for delivering material to the chambers of the basket for the separation of liquids from the sludge, and means for rotating the basket.

21. A centrifugal separating machine including a housing provided with a substantially annular sludge channel and having an outlet communicating with the channel, a horizontal rotary centrifugal basket having peripheral sludge discharge ports arranged to discharge sludge by centrifugal force into the said channel, a valve sleeve slidable on and rotating with the said basket and provided with portions arranged to cover and uncover the sludge ports, and blades mounted on the valve sleeve and operating in the channel for sweeping the sludge through the channel to the said outlet, and means for rotating the basket.

22. A centrifugal separating machine including a substantially cylindrical housing provided with removable side plates having inwardly extending annular flanges approximately L-shaped in cross section and cooperating with the side plates to form annular effluent troughs, a shaft extending across the housing and journaled in the side

- plates, a horizontal rotary centrifugal basket mounted on the said shaft and provided at its ends with seepage means located in the planes of the said troughs and arranged to discharge liquid from the basket into the said troughs, and means for rotating the basket.
23. A centrifugal separating machine including a substantially cylindrical housing provided with removable side plates having inwardly directed annular flanges cooperating with the side plates to form annular effluent troughs, a shaft extending across the housing and journaled in said side plates, a horizontal rotary centrifugal basket mounted on said shaft and provided at each end with seepage means located in the vertical planes of the said troughs and arranged to discharge liquid from the basket into the said troughs, and means for rotating the basket.
24. A centrifugal separating machine including a housing provided with side plates having vertically disposed annular flanges forming annular effluent troughs, said side plates being also provided at the upper portions of the troughs with arched flanges having grooves to facilitate collecting the effluent, a horizontal rotary centrifugal basket operating within the housing and provided with seepage means located within the vertical planes of said troughs for discharging liquid into the same, and spaced curved vanes in the troughs to receive the impact of the effluent discharged through said seepage means to conserve energy and to facilitate the collection of the effluent in the troughs and grooves and the draining of the effluent from the basket.
25. A centrifugal separating machine including a housing provided with side plates having vertically disposed annular flanges forming annular effluent troughs, said side plates being also provided at the upper portions of the troughs with arched flanges having grooves to facilitate collecting the effluent, said annular flanges being also provided at the bottom with approximately semi-circular gutters also for facilitating collecting effluent, a horizontal rotary centrifugal basket operating within the housing and having seepage means located in the vertical planes of the annular flanges and adapted to discharge the seepage liquid into the said troughs, and spaced vanes in the troughs to receive the impact of the effluent discharged through said seepage means to conserve energy and to facilitate the collection of the effluent in the troughs and grooves and the draining of the effluent from the basket.
26. A centrifugal separating machine for the separation of liquids from sludges including a housing provided with side plates having annular effluent troughs on the inner faces thereof, a horizontally disposed rotary centrifugal basket having the ends thereof overhanging the respective troughs and in the end walls thereof provided with seepage means for the discharge of

liquids tangentially of the basket into the troughs as the fluids are separated from the sludge during rotation of the basket, means for rotating the basket, and means for permitting discharge of the separated sludge from the basket.

27. A centrifugal separating machine including a housing provided with side plates having vertically disposed annular flanges forming annular effluent troughs, said side plates being also provided at the upper portions of the troughs with arched flanges having grooves to facilitate collecting the effluent, and a horizontal rotary centrifugal basket operating within the housing and having seepage means located within the planes of the said troughs for discharging liquid into the same.

28. A centrifugal separating machine including a housing provided with side plates having vertically disposed annular flanges forming annular effluent troughs, said side plates being also provided at the upper portions of the troughs with arched flanges having grooves to facilitate collecting the effluent, said annular flanges being also provided at the bottom with approximately semi-circular gutters also for facilitating collecting effluent, and a horizontal rotary centrifugal basket operating within the housing and having seepage means located in the planes of the annular flanges and adapted to discharge the seepage liquid into the said troughs.

29. A centrifugal separating machine for dewatering sewage sludge and similar materials comprising a hollow base providing an effluent receiving tank, a housing supported upon the base, a mixing and treating tank located above the housing and supported by the same and provided with means for feeding, cutting, stirring and agitating the sludge fed to said mixing and treating tank including a rotary horizontal shaft provided with blades, a horizontal rotary centrifugal basket operating within the housing and having a horizontal shaft extending through the basket and the housing and journaled in the latter, valved means for conveying the treated material in the mixing and treating tank through the housing and into the basket, means within the basket against which the treated material delivered to the basket impinges and by which the material is spread within the basket, troughs arranged within the housing, seepage means leading from the interior of the basket whereby to discharge liquids into said troughs, the troughs having communication with said hollow base to deliver the liquids to the hollow base, gearing for connecting one end of the horizontal shaft of the basket with the horizontal shaft of the mixing and treating tank, and a motor mounted upon the base of the machine adjacent the housing and close coupled to the other end of the horizontal shaft of the basket.

JOSEPH S. PECKER.
